UNITED STATES PATENT OFFICE.

GEORGE A. AMSDEN, OF LITTLETON, MASSACHUSETTS, ASSIGNOR TO THE LAMSON COMPANY, (FORMERLY LAMSON CONSOLIDATED STORE SERVICE COMPANY,) OF BOSTON, MASSACHUSETTS, A CORPORATION OF NEW JERSEY.

CABLE-CARRIER APPARATUS.

1,108,824.

Specification of Letters Patent. Patented Aug. 25, 1914.

Application filed November 23, 1912. Serial No. 733,116.

To all whom it may concern:

Be it known that I, GEORGE A. AMSDEN, of Littleton, in the county of Middlesex and State of Massachusetts, have invented certain new and useful Improvements in Cable-Carrier Apparatus, of which the following is a specification.

My invention relates to improvements in cable carrier apparatus and its object is to provide means for the despatch, transmission and receiving of carriers of the type shown and described in my United States Letters Patent No. 1,101,518, and particularly to provide means for placing such carriers into engagement with the driving cable for despatching the same and to disconnect the same from the cable for receiving said carriers.

In the accompanying drawings is illustrated a construction embodying my invention, in which,

Figure 1 is a plan view of one of the out or clerk stations showing means for receiving and despatching carriers. Fig. 2 is a sectional view on line 2—2, Fig. 1. Fig. 3 is a section on line 3—3, Fig. 1 and Fig. 4 is a section on line 4—4 Fig. 1 looking in the direction indicated by the arrow. Fig. 5 is a side elevation of Fig. 1, showing a carrier being placed in engagement with the driving cable for despatch. Figs. 6 and 7 are details of supporting brackets to be hereinafter described.

Like characters of reference refer to like parts throughout the several views.

A and A' represent the in-going tracks to the main station, and B and B' represent out-going tracks from the main station. These tracks are held in alinement and positionally secured by brackets X, Y and Z.

C represents an endless driving cable the ingoing portion indicated by the arrow, and normally resting upon and supported by the tracks A and A'. The out-going or oppositely moving portion of the cable as indicated by the arrow is supported by the tracks B and B'. The tracks A and A' are depressed below the cable C at D between the supporting brackets G and W, the track A' having an angular offset E therein suitable for the insertion of the carrier between the two tracks. The bracket G, see Figs. 1 and 6, supporting the tracks A and A' has a finger or guide H mounted directly over the

cable C and adapted to prevent the lifting of the cable at that point when a carrier is being despatched from the angular offset E. The tracks B and B' between brackets Y and Z at J are separated sufficiently to allow the carrier, when the same is switched at the station to pass through between the said tracks.

Located on the inner faces of brackets Z and Y at the receiving stations are graduated slots S into which the switch or delivery tracks N and supporting or guide tracks O are secured by suitable pins P. The switch tracks N are composed of two strips held slightly separated and mounted in slots S on opposite sides of brackets Z and Y and mounted at a pre-determined distance below tracks B and B', so that the guides or ears T on a carrier intended for that station will enter between the strips of switch tracks N and be deflected from the tracks B and B'. The rods K and K' secured to brackets Z and Y are slightly flared and receive and hold the carrier steady, so that it will properly enter switch tracks N.

M and M' are receiving tracks, the ends secured and supported by bracket Y being pointed and adapted to support the fiber plate U of the carrier when the same leaves switch track N. These tracks M and M' at the opposite ends are supported by bracket X (see Fig. 4), the end of track M' being rigidly secured to said bracket while the end of track M is secured to an arm X' pivoted at X' and which is connected with the opposite side of bracket X by a suitable spring which acts to hold the ends of tracks M and M' together forming a spring brake to hold the carrier thereon until removed by the clerk.

Guide tracks O are mounted in certain slots S and in position to engage the guides or ears T of carriers not intended to deliver at this station and to support the same while passing by openings J in tracks B and B' while the rods L and L' serve to engage the sides of the fiber plate U on the carrier to steady the same until it picks up the tracks B and B' again.

In despatching a carrier, such as is shown in my application filed simultaneously herewith, from the clerk's station to the cashier's or main station the clerk inserts the carrier into the angular offset E and pushes

2
the carrier up the incline of tracks A and A' (see Figs. 1 and 5) until the clamp Q reaches the cable and engages the same causing the carrier to be transmitted to the main station. In the meantime the finger or 5 guide H serves to hold the cable C while the clamp Q is engaging the same thereby assisting the engagement of the clamp with said cable. In fact the element H may properly be said to pry or wedge the cable into 10 the clamp or grip of the carrier.

If a carrier is despatched from the cashier's station to the sub or clerk's station shown in Fig. 5, the carrier is transmitted 15 by the out-going portion along tracks B and B' until it arrives at the switch N. The carrier now enters the rods K and K' which serves to steady the carrier while the guides or ears T of the carrier enter the switch 20 tracks N causing the carrier to be deflected along said switch through opening J in tracks B and B' at the same time pulling the clamp Q out of engagement with the cable C. The carrier now moves by momentum 25 until it rides upon the tracks M and M' and is stopped thereon by action of the brake X' and remains until the operator slides the carrier through between said tracks. If a carrier intended for another station arrives, 30 the guides or ears T being located at a different graduation thereon it passes into the guide tracks O being supported by rods L and L' until the carrier has passed the opening J and is again supported by the tracks 35 B and B'.

Having thus described the nature of my invention and set forth a construction embodying the same, what I claim as new and desire to secure by Letters Patent of the 40 United States is:

1. In a cable carrier apparatus, a track or way, a cable for driving carriers along said track or way, a carrier having a grip adapted to engage said cable by being thrust 45 thereagainst, means whereby carriers may be placed into coöperation with said track or way and into operative engagement with said cable, and means to resist lateral displacement of said cable at the point therein 50 against which said grip is exerting a thrust action as said grip is being placed in operative engagement with said cable.

2. In a cable carrier apparatus, a track or way, a cable for driving a carrier along said 55 track or way, carriers adapted to travel on said track or way and having a grip for engaging said cable, means whereby said carrier may be placed into coöperation with said track or way, and means for tilting 60 said grip of said carrier with respect to said cable when said grip is being driven into engagement with said driving cable.

3. In a cable carrier apparatus, a track or way, a cable for driving a carrier along said 65 track or way, carriers adapted to travel on

said track or way and having a grip adapted to engage said cable by being thrust thereagainst, means whereby said carrier may be placed into coöperation with said track or way, means for tilting the grip of 70 said carrier with respect to said cable when said grip is being thrust into engagement with said driving cable, and a support or guide adapted to resist the thrust against said cable when said grip is being engaged 75 with said cable.

4. In a cable carrier apparatus, a track or way, a cable for driving a carrier along said track or way, carriers adapted to travel on said track or way and having a grip thereon for engaging said cable, said track having means whereby said carrier may be inserted 80 into coöperation therewith and also having a portion inclined to said cable to guide said carrier with its grip theretoward, said grip being inclined with respect to said cable 85 when being engaged therewith.

5. In a cable carrier apparatus, a track or way, a cable for driving carriers along said track or way, a carrier adapted to travel 90 along said track or way and having a spring clamp adapted to yield to receive said cable when thrust into operative engagement therewith, means whereby when said cable is held against lateral movement to resist said thrust, said carrier may be placed into coöperation with said track or way and with said cable, and means for holding said cable against lateral movement to resist the thrust of said clamp when the latter is being engaged with said cable. 95

6. In a cable carrier apparatus, a track or way, a cable for driving carriers along said track or way, a carrier adapted to travel on said track or way, a grip located on said carrier and having two jaws adapted to grip 100 said cable, means for placing said carrier into coöperation with said track or way, and means for pushing said cable between said jaws for operatively engaging the latter 110 with said cable whereby the carrier is thereafter transmitted along said track or way. 115

7. In a cable carrier apparatus, a track or way, a cable for driving carriers along said track or way, a carrier adapted to travel 115 on said track or way and having a grip adapted to resiliently engage said cable, and means for diverting said carrier from said track or way whereby said grip is pulled out of engagement with said cable, said grip 120 yielding to the wedging action exerted thereagainst by said cable.

8. In a cable carrier apparatus, a track or way, having an opening located therein, a cable for driving carriers along said track or way, carriers adapted to travel on said track or way and having a resilient clamp adapted to engage said cable, a receiving track, and a switch for pulling carriers out of coöperation with said cable and diverting said 125 130

carriers through said opening on to receiving track, said resilient clamp being adapted to be wedged open by said cable when said switch guides the carrier away from said cable.

9. Cable carrier apparatus comprising a track, a carrier to travel thereon, a cable to propel said carrier along said track, said carrier having a clamp adapted to operatively engage said cable when said cable is wedged thereinto, and means for wedging said cable into said clamp.

10. Cable carrier apparatus comprising a track, a carrier to travel thereon, a cable to propel said carrier along said track, said carrier having a clamp adapted to operatively engage said cable when said cable is wedged thereinto, and means to directly engage said cable and pry it into said clamp.

11. In a cable carrier apparatus, a track

or way, a cable for driving carriers along said track or way, a carrier having a grip adapted to engage said cable simply by being thrust thereagainst, means whereby carriers may be placed into coöperation with 25 said track or way and into operative engagement with said cable, and means to resist lateral displacement of said cable at the point therein against which said grip is exerting a thrust action as said grip is being 30 placed in operative engagement with said cable.

In witness whereof, I have signed my name to this specification in the presence of two subscribing witnesses, this 17th day of 35 Sept., 1912.

GEORGE A. AMSDEN.
